UNITED STATES PATENT OFFICE.

STEFAN STEINMETZ, OF BERLIN, GERMANY.

PROCESS FOR THE REMOVAL OF THE CEREALINS AND DRYING OF GRAIN MOISTENED FOR THIS PURPOSE.

Application filed November 6, 1926, Serial No. 146,697, and in Germany October 19, 1925.

The bran, that is the wrapper which covers the kernel of the grain consists, as is well known, of two different layers. The outer layer or so-called cellulose tissue, is 8 worthless for human nourishment and is almost hygroscopic.

The removal of this cellulose layer by a wet process and by means of peeling and centrifugal devices is well known. The inner layer, the "aleuron" or faveolate layer is like leather and offers a very great resistance against entrance of water. These two layers are fixed together and provided by nature with a certain sticking ferment. 15 Mege-Mouries, who has discovered this ferment as early as in the middle of the nineteenth century has given to the same the name "cerealine." To the presence of this ferment the extreme acetous fermentation of 20 the bread-dough, the darkening of its colour and the bad digestibility of the bread are attributed. It is known to experts, that the action of these disagreeable characteristics entirely depends upon the degree of removal 25 of this sticking ferment or "cerealine". If the latter is carefully removed, the bread becomes of a lighter color and the quantity of acetous contents therein will be reduced.

By washing and peeling the grains by a 30 wet process it will be possible to partially remove this sticking ferment. This process, however, is connected with the grave disadvantage, that the machines used for carrying out the same will become soiled very 35 easily. Furthermore, experience has shown, that cold water alone will not be sufficient for carrying out this process, and that furthermore the drying and polishing of the grains leaves much to be desired, if the main 40 purpose of the process consists in the entire removal of the "cerealine". The above statements will serve in order to facilitate the better understanding of the invention, which has for its primary object to absolutely re- 45 move the "cerealine" and at the same time to again bring the grains into dry condition.

This invention consists essentially therein, that the grains are soaked and washed in a single process by a positive motion of the 50 same, and thereupon exposed likewise by positive motion to such intimate friction between each other that in the working containers there will be produced such a degree of heat, that the heat on the one hand will 55 facilitate the removal of the "cerealine" and

on the other hand act favourably upon the process of drying the moistened grains, as early as they leave the last working machine. According to this invention the drying of the grains by positive motion is accomplished by means of hinged plates, which are disposed in front of the outlets of the working containers so as to close up said outlets by the action of springs or weights. Such hinged plates are 60 known for instance in connection with mills and dissolving machines.

The accompanying drawing shows an illustration of a plant working according to this invention. Fig. 1 is in part a vertical section, and in part a longitudinal view of the machinery for carrying out the process according to this invention. Fig. 2 is a side view of the machinery shown in Fig. 1, and Fig. 3 a cross-section through the working containers of the machinery according to Figs. 1 and 2.

The corn, moistened with water in any well known manner, is conveyed in positive motion by means of a conveyor spiral 1, 80 while the outlet of the conveyor is closed by the yieldingly hinged plate 2, which is kept in closed condition by a weight or spring attached thereto. As soon as a certain pressure is generated during the motion of 85 the corn in the casing or container 3, the plate 2 will open automatically and the grain together with the water may pass said hinged plate and enter into the drum 4. In this drum the free water may discharge 90 through the sieve 5, while the moistened grains will enter into the drum 6. The stroke ledges 7 will now press the grains towards the inner wall of the drum, which may be fixedly or rotatably mounted. In 95 order to fill the drum 6 as near as possible up to the inner wall the ledges 7 are provided with perforations 7^a and in addition to this the outlet of the drum 6 contains a hinged plate 8, which is weighted on its out- 100 side and thus give way to the grain only after the latter is subjected to a relatively high pressure.

As the preliminary drum 6 is working without ventilation the increased friction of 105 the grains will produce heat, which will preliminarily and thoroughly soften not only the outside layer or tissue of cellulose, but also the layer of "cerealine" by means of the water, which becomes lukewarm due to said 110

friction. By means of the hinged plate 8 the outlet of the grains will be automatically regulated under pressure. The warmed grains together with the removed and loosened hulls are now entering the peeling drum 9, in which the hulls will be removed in the known manner by friction and carried away by the suction ventilator. In this drum also the work is done under an increased inner frictional pressure, because the outlet of this drum is likewise provided with a hinged plate 10, which is acted upon by a weight or spring. By means of the heat, which will thus be produced in combination with the action of the suction ventilator the grains are dried to such an extent that they will again almost assume their normal degree of dryness.

The "cerealine," however, after this procedure will not yet be absolutely removed. This is accomplished by the subsequent steps of operation of the plant, for which the aforescribed operations are the preliminary steps. The device serving for the subsequent operations consists of a centrifugal washing device 11 and a polishing machine 13. In the centrifugal device the entering grain will be impinged upon in the full width of the washing space by a jet of pressure water which may be mixed with chalk or other chemical substances which are not injurious to human health.

Thereupon the polishing machine, which is equipped with a shaft having stroke ledges 13 will perform the separation of the water, which had again been added, and thoroughly and finally remove the "cerealine" and polish the grains in dry condition.

The passage of the grains from the centrifugal device 11 into the polishing room takes place through a top opening 14, provided in the separation wall 15.

The polishing machine is likewise connected with the suction ventilator, the stroke ledges 16 of the polishing machine being also provided with perforations, which are directed towards the outside, and the outlet also is provided, the same as before, with a hinged plate and weights or springs therefor. The purpose is, as before, to obtain by friction a sufficient degree of heat for dis-

solving the "cerealine" and to dry the grains. The suction ventilator removes also the dust together with the "cerealine."

The process according to this invention may also be performed, with existing peeling devices by providing the described hinged plates on the outlets with these devices, and by connecting the apparatus with a centrifugal washing device and a polishing machine 11 and 12.

It will be understood, that no part of the plant herein described, which serves for carrying out the process according to this invention, is a new device, when considered for itself. According to this invention a considerable progress is attained by the hinged plates for the purpose of producing a new effect by the heat which is generated in the apparatus. In ordinary mills and dissolving machines the heat generated therein will exert an injurious effect upon the baking capacity of the material and for the preservation of the gluten cells and must therefore be as far as possible avoided. According to the present invention, the heat is intended to be produced and used for a useful purpose, viz, for the removing of the "cerealine" and for drying the moistened products.

I claim:

A process for removing the "cerealine" from grains, which consists in soaking the grains in a single uninterrupted process and during positive motion of the same, washing said grains, thereupon exposing said grains under exclusion of ventilation to an interior friction, so as to raise the temperature in the vicinity of the grains to such an extent, that the water carried along with the grains will become lukewarm and thus be able to soften the cerealine and partly dissolve the same, thereupon rubbing and sucking off the so loosened and detached shells in the known way from the grains, again washing the grains with pressure water, polishing said grains in a polishing machine, and liberating said grains by action of centrifugal force from the moisture adhering thereto.

In testimony whereof I have affixed my signature.

STEFAN STEINMETZ.
